CLAIM

The ornamental design for an outsole for a shoe, as shown and described.

DESCRIPTION

FIG. 1 is a bottom perspective view of an outsole for a shoe in accordance with the new design;

FIG. 2 is a bottom view thereof;

FIG. 3 is a left side view thereof;

FIG. 4 is a right side view thereof;

FIG. 5 is a front view thereof; and,

FIG. 6 is a rear view thereof.

The broken lines shown in the arch area of FIGS. 1-2 represent boundaries of the design with the lines themselves and the areas within them forming no part of the claim.
